ELECTRIC VALVE CONTROL SYSTEM

Harold Winograd, Milwaukee, Wis., assignor to Allis-Chalmers Manufacturing Company, Milwaukee, Wis., a corporation of Delaware

Application July 26, 1934, Serial No. 736,978

5 Claims. (Cl. 175—363)

This invention relates in general to improvements in electric valve control systems, and more particularly to circuits for energizing control electrodes of a valve for controlling the operation thereof.

Electric valves of the vapor type are frequently associated with alternating current windings to constitute alternating current rectifying, direct current inverting, frequency changing and other current translating systems. In such systems, it is generally advantageous or even necessary to energize the control electrodes of the valve with periodic potentials, each control electrode being brought to a negative potential to prevent or delay the flow of current through the associated anode until the proper time in the voltage cycle of the winding associated with the valve, and being brought to a positive potential with respect to the cathode to release such flow of current. To cause interruption of the flow of current through the valve it is generally preferred to utilize the action of the control electrodes which, upon being brought to a negative potential with respect to the cathode, will prevent further sequential establishment of the flow of current through the anodes of the valve.

Between operating periods of each anode in the course of normal operation of the valve, and also at times of negative energization of the control electrode for causing interruption of the flow of current through the valve, each control electrode may accomplish its purpose of preventing the establishment of flow of current through the associated anode only after first collecting the charges of positive ions present in the space thereabout, such collection causing the flow of current from the control electrode to the energizing circuit therefor. Such current is of limited intensity and should encounter only comparatively low impedance to permit the most efficient action of the control electrode. In the contrary condition, when a control electrode is at a positive potential, the current flow from the energizing circuit to the control electrode is limited only by the impedance of the circuit, and such impedance should be maintained at a high value to reduce the system losses caused by the flow of such current.

It is therefore one of the objects of the present invention to provide a control system for an electric valve in which the impedance of a control electrode circuit is of different values for the two directions of flow of current therethrough.

Another object of the present invention is to provide a control system for an electric valve in

which each control electrode circuit includes an impedance which is bridged by an electric valve.

Another object of the present invention is to provide a control system for an electric valve by means of which the space about each control electrode is rapidly deionized upon negative energization of the control electrode.

Another object of the present invention is to provide a control system for an electric valve in which the application of negative potential to the control electrode from a voltage source is accelerated to the greatest possible extent.

Objects and advantages other than those above set forth will be apparent from the following description when read in connection with the accompanying drawings, in which:

Figure 1 diagrammatically illustrates one embodiment of the present invention applied to the control of an electric valve controlling the flow of energy between a direct current line and an alternating current line; and

Figure 2 diagrammatically illustrates a portion of a modified embodiment of the present invention differing from the embodiment illustrated in Figure 1 in the use of a single auxiliary electric valve, rather than a plurality of such valves, for controlling the flow of current through a plurality of control electrode circuits.

Referring more particularly to the drawing by characters of reference, reference numeral 6 generally designates an electric valve of the discontinuously controllable type utilized for controlling the flow of current between an alternating current line 7 and a direct current line 8. The anodes 9 of valve 6 are severally connected with the phase displaced portions of one winding 11 of a transformer 12 having another winding 13 thereof connected with line 7. Winding 11 may be connected with one of the conductors of line 8 either directly or through an interphase transformer 14 as is well known in the art. Valve 6 is also provided with a cathode 16 connected with the other conductor of line 8. The potential of cathode 16 will herein be used as datum for potentials and all potentials will be referred thereto, a source of voltage connecting an element of the valve with the cathode then impressing on such element a potential component equal to the voltage of such source. Valve 6 is also provided with the usual means for bringing and maintaining part or all of cathode 16 at incandescence, such means being well known in the art and therefore not shown.

The flow of current through valve 6 is controlled by suitable discharge controlling means

such as control electrodes 17 each connected with cathode 16 by means of a control electrode circuit including one or more sources of control voltage. In the description of the present embodiment it will be assumed that direct current obtained from line 8 is to be converted into alternating current to be supplied to line 7. As is well known, each control electrode 17 may then be at a positive potential only during a portion of the voltage cycle which is, at the most, not materially longer than the operating period of the associated anode. To obtain such control electrode energization, each control electrode may be connected with one of the phase displaced portions of the secondary winding 18 of a transformer 19 having a primary winding 21 energized from line 7. The core 22 of transformer 19 and the winding 21 are preferably so dimensioned that the core is highly saturated when the voltage of line 7 is at the normal value thereof, with the result that the voltage of each portion of winding 18 presents sharp peaks instead of being sinusoidal. The neutral point of winding 18 is preferably connected with cathode 16 through a source of unidirectional voltage such as a voltage divider 23 connected across a suitable source of direct current voltage such as a battery 24. The connection of winding 18 with voltage divider 23 is such as to cause the impression on each control electrode of a negative unidirectional voltage component of a magnitude somewhat less than the peak value of the voltage of winding 18, so that each control electrode becomes positive only during the peak of the voltage wave of winding 18 and is at a negative potential during the remainder of the voltage cycle.

Each control electrode circuit includes suitable impedance means such as a resistor 26 of comparatively high value and another resistor 27 of comparatively low value. Each resistor 26 is bridged by an electric valve 28 of any suitable type which is so connected as to conduct current flowing from control electrodes 17 to the associated circuit 15. The moment of the voltage cycle at which the control electrode is brought to a positive potential may be varied by shifting the phase of the voltages of transformer 19 by means of a phase shifter 29 inserted in the connection between line 7 and winding 21. For the purpose of causing interruption of the flow of current through valve 28 upon occurrence of a disturbance in the system, the system is provided with means responsive to the occurrence of such disturbances such as relays 31 and 32 having the coils thereof energized from a current transformer 33 inserted in the connection between winding 13 and line 7. Relay 31 normally completes the connection between the neutral point of winding 18 and voltage divider 23 and, upon operation thereof, connects the neutral point of winding 18 with the negative terminal of battery 24. Operation of relay 32 causes short circuiting of phase shifter 29 or of winding 21 to substantially suppress the alternating voltage component impressed on control electrodes 17, the flow of current through the contacts of relay 32 being limited by suitable impedance means such as resistors 34.

In operation, the system being connected as shown in the drawings, each control electrode receives a peaked alternating voltage component from one of the portions of winding 18, such component being superposed on a negative voltage component received from voltage divider 23.

Each control electrode is thus maintained at a negative potential during the greater part of the voltage cycle of line 7 and becomes positive once per cycle for a short time interval. The phase relation between the associated portions of windings 11 and 18 is so adjusted that when a control electrode 17 becomes positive, the associated anode 9 is receiving an increasing negative voltage from the associated portion of winding 11, such voltage being however smaller in magnitude than the voltage then received by the anode at that moment carrying current. The anode 9 now being considered is then at a positive potential with respect to the operating anode and to the cathode, and the flow of current is transferred thereto upon the associated control electrode becoming positive. Such control electrode remains positive for a short period of time, the flow of current from the associated circuit thereto being limited by resistors 26 and 27.

While the associated anode is still carrying current, the control electrode again becomes negative. The control electrode is then able to collect the charges of positive ions present in the space thereabout, such charges being neutralized by the negative charges supplied by the joint action of battery 24 and winding 18 or, in other words, such charges are removed by the flow of an inverted current from control electrode 17 to the control circuit. If the control electrode is of the usual type, such flow of current is without action on the anode current and, when the latter current ceases as a result of the anode becoming negative with respect to the cathode, the control electrode current continues to flow until the space about the control electrode is substantially free of ions. When the control electrode is given suitable dimensions however, it may collect the charges of ions present in the arc path of the associated anode at a rate greater than the rate of appearance of such ions, the arc path then becomes deionized and the anode current is actually interrupted.

In either case the flow of inverse current through the control electrode circuit causes a voltage drop therein which raises the potential of the control electrode and delays the application thereon of the full negative potential of the source, which is necessary for producing an electrostatic field to prevent renewed flow of current through the associated anodes until further reversal of the control electrode polarity. As a result of the presence of valve 28, the impedance of the control circuit to the flow of inverse current is reduced to that offered by resistor 27, or even to substantially the resistance of the sources if resistor 27 is omitted, so that deionization may occur freely and application of the negative potential of battery 24 of the control electrode is accelerated. Such action causes the negative electrostatic field to be rapidly established about the control electrode, and the anode is blocked with the least delay, thereby preventing any undesired reattachment of an arc thereto between successive operating periods.

Upon the occurrence of a disturbance causing the flow of excessive current in winding 13, current transformer 33 energizes the coils of relays 31 and 32 with current of magnitude such as to cause operation of such relays. Relay 31 then connects the neutral point of winding 18 with the negative terminal of battery 24, thereby impressing an increased negative unidirectional voltage component on all the control electrodes. Relay 32 short circuits phase shifter 29, so that

transformer 19 becomes substantially without current and simply transmits the negative potential of battery 24 to the control electrodes. Upon such occurrence, the control electrodes must also rapidly deionize the space thereabout to prevent the re-establishment of the flow of current through the associated anodes, and thereby rapidly cause interruption of the flow of current through valve 6. Such action is also accelerated by the flow of inverse current from the control electrodes through valves 28 instead of through resistors 26. While the operation of the system illustrated in Figure 1 was described, assuming the system to perform as an inverting system, it will be understood that by suitably modifying the phase relation between the voltages of associated portions of windings 11 and 18, the system will operate as a rectifying system, the action of the control electrodes then remaining identically that above described. Such action would also be maintained in any other systems utilizing a valve of the type of valve 6.

The embodiment partly illustrated in Figure 2 is more particularly useful to control the supply to line 8 of alternating current received from line 7 and rectified in valve 6. In the present embodiment, transformer 19 is shown as being provided with a delta-connected primary winding 36 so connected as to obtain the proper phase relation between the voltages of associated portions of windings 11 and 18. During rectifying operation of valve 6, the rapid deionization of the arc path about the anodes between successive operating periods thereof is not absolutely necessary and resistors 26 and valves 28 may therefore be omitted. The flow of current through the control electrodes during the period of positive energization thereof may then be limited by means of a common resistor 37 inserted between the neutral point of winding 18 and voltage divider 23. Resistor 37 is bridged by means of an electric valve 38 permitting the flow of current from control electrodes 17 to their associated control circuits. A plurality of resistors 39 may be inserted between the contacts of relay 32 and winding 36 to cause rapid dissipation of the magnetic energy stored in the core 22 upon operation of relay 32. Battery 24 is shown as being connected with cathode 16 through a second voltage divider 40 connected in parallel with voltage divider 23. The positive portion of voltage divider 40 may be short circuited by the contacts of relay 31, a capacitor 41 being connected across such contacts to avoid arcing thereof upon release of the armature of the relay.

It will be understood that, if it is not desired to utilize control electrodes 17 for regulating the voltage of line 8, transformer 19 may be omitted and the tap of voltage divider 23 may be moved to the positive portion thereof to constantly impress a positive voltage on all the control electrodes 17 and thereby facilitate the attachment of the arc to the several anodes 9 in succession.

Upon occurrence of a disturbance causing operation of relay 31, the positive terminal of battery 24 is connected with cathode 16 through the contacts of the relay and all the control electrodes then receive only a negative potential of magnitude corresponding to the position of the tap of voltage divider 23. If transformer 19 is present, such transformer is again rendered inoperative by means of relay 32. The operation of control electrodes 17 to cause interruption of the flow of current through valve 6 is then iden-

tical to that of the control electrodes in the embodiment illustrated in Figure 1 and need not therefore be repeated.

Although but two embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In an electric translating system, a discontinuously controllable electric valve having an anode with an associated control electrode and a cathode, and a control electrode circuit for said valve including a source of positive and negative voltages, a resistor serially connected with said source to conduct current flowing through said circuit when said control electrode is at a positive potential with respect to said cathode, and an auxiliary electric valve connected across said resistor to conduct current flowing through said circuit when said control electrode is at a negative potential with respect to said cathode.

2. In an electric translating system, a discontinuously controllable electric valve having an anode with an associated control electrode and a cathode, and a control electrode circuit for said valve including a source of control voltages, a resistor serially connected with said source to limit the flow of current through said control electrode when the control electrode is at a positive potential with respect to the cathode, means for maintaining said control electrode at a negative potential with respect to said cathode to cause interruption of the flow of current through said valve, and an auxiliary electric valve connected across said resistor to accelerate the application of said negative potential to said control electrode.

3. In an electric translating system, an alternating current winding, an electric valve of the vapor type connected with said winding and having an anode with an associated control electrode and a cathode, and a control electrode circuit for said valve including a source of control voltages, a resistor serially connected with said source to limit the flow of current through said control electrode when the control electrode is at a positive potential with respect to the cathode, means responsive to an operating condition of said valve for maintaining said control electrode at a negative potential with respect to said cathode to cause interruption of the flow of current through said valve, and an auxiliary electric valve connected across said resistor to accelerate the application of said negative potential to said control electrode.

4. In an electric translating system, an alternating current winding, an electric valve of the vapor type connected with said winding and having an anode with an associated control electrode and a cathode, and a control electrode circuit for said valve including a source of alternating voltage and a source of unidirectional voltage, a resistor serially connected with said sources to limit the magnitude of the pulsating current flowing from said circuit to said control electrode, means responsive to an operating condition of said valve for modifying the voltages impressed on said circuit by said sources to maintain said control electrode at a negative potential with respect to said cathode, and an aux-

illiary electric valve connected to bridge said resistor for the flow of current from said control electrode to said circuit whereby the space about said control electrode is rapidly deionized upon 5 application of said negative potential on the control electrode.

5. In an electric translating system, an alternating current winding, an electric valve of the vapor type connected with said winding and having a plurality of anodes with associated control electrodes and a cathode, and control circuits 10 for said control electrodes including sources of alternating voltages, a common source of uni-

directional voltage connected with said circuits, a resistor serially connected with said sources to limit the flow of current from said sources to said control electrodes, means responsive to an operative condition of said valve for causing said sources to impress a negative potential on said control electrodes to cause interruption of the flow of current through said valve, and an auxiliary valve bridging said resistor for the flow of inverse current from said control electrodes to 10 said sources. 5

HAROLD WINOGRAD.
